UNITED STATES PATENT OFFICE.

HERMAN MOSCHEL, OF OTTUMWA, IOWA, ASSIGNOR TO DAIN MANUFACTURING COMPANY OF IOWA, OF OTTUMWA, IOWA, A CORPORATION OF IOWA.

EXTENSIBLE HAY-STACKER.

1,318,788.

Specification of Letters Patent. Patented Oct. 14, 1919.

Application filed August 19, 1918. Serial No. 250,513.

To all whom it may concern:

Be it known that I, HERMAN MOSCHEL, a citizen of the United States, and a resident of Ottumwa, in the county of Wapello and State of Iowa, have invented certain new and useful Improvements in Extensible Hay-Stackers, of which the following is a specification, reference being had to the accompanying drawings.

10 My invention relates to hay stackers of the overshot type, in which the hay is deposited upon a head carried by a swinging frame, and is carried up over the stacker and discharged upon a stack located back of it by the swinging of such frame. It has particularly to do with stackers of this description in which provision is made for varying the height at which the hay is discharged from the stacker by mounting the stacker head upon an extensible frame which is carried by a swinging lifting frame connected with the hoisting mechanism.

One of the objects of my invention is to so arrange the parts and correlate their action that the draft required to operate the stacker is lightened. Another object is to provide improved lever mechanism for hoisting and lowering the stacker head and advancing or retracting the same, so that the stacker will operate smoothly and without destructive strain. A further object is to provide a construction that can be adjusted either to operate as an ordinary overshot hay stacker without automatic extension, 30 and retraction of the stacker head occurring, or to cause automatic extension and retraction of the stacker head to occur. I accomplish these objects as illustrated in the drawings and as hereinafter described. What I 35 regard as new will be set forth in the claims.

In the drawings:

Figure 1 is a plan view;

Fig. 2 is a side elevation, the relative position of the parts as the lifting action begins being shown in full lines, the dotted lines showing the relative position of the parts when the stacker head is partially raised;

Fig. 3 is a side elevation with the stacker head in load delivering position;

Fig. 4 is a cross section on the line 4—4 of 50 Fig. 2;

Fig. 5 is a section on the line 5—5 of Fig. 3; and

Fig. 6 is a detail showing the rocking support for the stacker head arms upon the 55 lifting arms.

My improved stacker comprises a suitable base adapted to support the operating parts of the machine, a swinging lifting frame pivotally mounted upon the base so as to 60 swing in a vertical plane from a substantially horizontal position to a point somewhat beyond the perpendicular, an extensible frame adjustably mounted upon the lifting frame and carrying the stacker head, 65 mechanism for automatically moving the extensible frame relatively to the lifting frame as the latter is raised or lowered, and hoisting mechanism consisting of a system of levers, pulleys, and a hoisting rope arranged to be operated by draft animals. The novel feature of my improved stacker will be pointed out in connection with the following detailed description of the embodiment thereof illustrated in the drawings.

The stacker base is formed of parallel spaced sills 10—11, connected by a front cross sill 12, a rear cross sill 13, and an intermediate cross sill 14. Outwardly diverging braces 15 extend from the center of the rear cross sill to the sills 10—11. Mounted upon the outer ends of the diverging braces, 80 are brackets 16—17 which have outwardly extending pins 16^a—17^a that form pivots 85 upon which the swinging lifting frame is mounted. The lifting frame is composed of side members or arms 18—19, the forward ends of which are connected by a cross bar 20, the arms and cross bar being braced by 90 triangular plates 21—22. Rockingly and slidably supported upon the lifting frame by means which will be hereinafter described, is the extensible frame which comprises arms 23—24 which at their forward 95 ends support the usual stacker head, composed of the transverse bars 25—26, the stacker teeth 27, and the pitcher teeth 28,

pivotedly mounted on the stacker teeth and connected together with the transverse bar 29. The pitcher teeth are adjusted relatively to the stacker teeth by means of the 5 strap and hook means 30. 31—32 indicate braces that diverge outwardly from the arms 23—34 of the extensible frame and aid in supporting the end portions of the stacker head.

10 The lifting frame is hoisted by means of the usual mechanism consisting of an A frame composed of bars 33—34 pivotally supported upon the base and having pivotally mounted in its apex a lever 35, the 15 forward end of the lever being connected with the triangular shaped plates 21—22 of the lifting frame by diverging rods 36—37, the rearward end of the lever being connected with the rear sill 13 by a block and tackle means 38. A spreader 39 secured between the bars 33—34 prevents the A frame from buckling. When the stacker head is in load receiving position, the hoisting mechanism is held in proper operative 20 position by a chain 40 extending between the forward end of the lever 35 and the diverging braces 15. When the stacker head is elevated, this chain of course is slack, as indicated in Fig. 3. The lifting frame is 25 prevented from passing too far beyond the perpendicular at the delivery point by stop ropes 41—42 secured at their upper ends to the lifting frame and after passing over blocks 41^a—42^a are connected to sleeves 30 41^b—42^b slidably mounted on tubular bars 45—46, and arranged to bear against cushioning springs 43—44 mounted on the bars 45—46 as shown in Fig. 1. The bars 45—46 are secured to the front cross sill 12, the 35 intermediate sill 14, and the parallel sills 10—11, and form pivot bearings for the A frame as well as supports for the sliding sleeves and cushioning springs.

When the lifting frame is hoisted, the extensible frame and the stacker head are automatically moved relatively to the lifting frame both angularly and longitudinally by mechanism now to be described.

Secured to each lifting frame arm 18—19 40 is a bearing block 47, as best shown in Fig. 4. Pivotedly supported upon each bearing block and spaced apart a distance sufficient to provide ample clearance for the arms 23—24 of the extensible frame to move 45 therebetween, is an outside bracket 48 and an inside bracket 49. The pivot which supports said brackets is indicated by 47^a in Figs. 2 and 4. The bracket 48 is provided with a forward arm 50 and a rearward arm 52, and the bracket 49 is provided with a 50 forward arm 51 and a rearward arm 53. The arms 50—52 and the arms 51—53 thus form parallel bell crank levers spaced apart to admit of the passage therebetween of the

arms 23—24 of the extensible frame. As 65 indicated at *a* in Fig. 1 the end of each arm 50—51 is beveled or rounded to provide an inclined surface so as to prevent the arms 23—24 of the extensible frame from locking with the arms 50—51. The ends of 70 the arms 50—52 are connected by a truss or stiffener brace 54, which is reinforced and armored with a metal strip 55 riveted thereto, and the ends of the arms 51—53 are likewise connected by a similar truss or 75 stiffener brace. The forward arm 50 of each outside bell crank lever is connected with the sill 10 by a strap 59, and the forward end of each inside bell crank is connected with the sill by a strap 59^a, as shown in 80 Fig. 1, said straps being spaced apart so that the lifting frame arms and the arms of the extensible frame can operate between them. The strap 59 is reinforced by a wooden bar 56, and the opposite side of said 85 bar is connected with the arm 50 by a strap 58, as shown in Fig. 3. In like manner the strap 59^a is reinforced by a wooden bar 57 and the side of said bar is connected with the arm 51 by a strap 58^a.

The medium of connection for the straps 59 and 59^a and their reinforced bars 56—57 to the sill consists of an outstanding bracket 60 secured to the side of the sill and having a spreader 61, as best shown in Figs. 3 and 95 5, the straps and bars being pivotally secured to the bracket and spreader by a bolt 61^a.

The rear arms 52—53 of each bell crank lever are pivotally connected with the arms 100 23—24 of the extensible frame by pivots 62, as shown in Figs. 2 and 3, and are provided with a series of alined holes that register with a series of holes in the arms 23—24 for receiving said pivot and adjusting the point at which said members are connected to each other, as the extent to which the stacker head is extended and retracted during the raising or lowering of the lifting frame depends upon the holes that are 110 used for pivoting the bell crank levers and the extensible frame arms 23—24 together. The pivot 62 is illustrated in the drawings as being in the set of holes farthest from the pivot 47^a of the bell crank levers and 115 therefore the stacker is set to project the head to the greatest extent. If it be desired to operate the stacker without any extension or retraction of the head, as for instance, when building the base and lower 120 portion of the stack, the pivots 62 of the bell crank levers are removed and inserted in the vertically positioned holes 63—63^a through the arms 23—24 and 18—19, shown in dotted lines in Fig. 2. When thus secured together, the lifting and extensible frames operate as an ordinary overshot hay 125 stacker. The bell crank levers at such time

rock by reason of the hinges 48-49 being connected with the arms of the lifting frame, but they perform no function.

When the bell crank levers are connected with the arms 23-24 of the extensible frame, as shown in the drawings, so that the machine operates as a self-extension stacker, the extensible frame rocks and slides longitudinally relatively to the lifting frame in the following manner: As best shown in Fig. 6, there is secured to the upper face of each arm 18-19 of the lifting frame at its outer end, a plate 64, having an upturned portion 65 that contacts with a shoe 66 positioned underneath each of the arms 23-24 and forms a pivot bearing between the plate and shoe. Each side of the shoe is provided with outwardly projecting lugs 67-68 that lie at opposite sides of a clip 69 secured to the cross bar 20, which clip 69 extends over the arms 23-24, said arms sliding therethrough as the lifting frame is elevated. Enough freedom of movement is provided between the lugs 67-68 and the clip 69 to permit the shoe 66 to rock upon the pivot bearing 65 and conform to the angle assumed by the extensible frame. When the stacker is in delivering position, the clip 69 holds the arms 23-24 from separating from the arms 18-19 of the lifting frame.

In operating the stacker, the draft animals attached to the rope raise the lifting frame through the medium of the block and tackle mechanism and the A frame hoisting device, and as the lifting frame rocks about its pivots upon the base, the bell crank levers are caused to actuate, their pivots being raised with the lifting frame, and as the forward ends of the bell crank levers are pivotally connected with the base, and spaced a fixed distance therefrom by the straps 59-59^a, the rearward arms of the bell crank levers which are connected with the arms of the extensible frame are caused to rock upwardly, which brings about movement of the extensible frame relative to the lifting frame. During the first stages of the hoisting operation, the arms of the extensible frame throughout their entire length are lifted substantially horizontally, in contradistinction to all other types of self-extending or sliding head stackers in which the extensible frame and the lifting frame together are swung in an arc about the pivot of the lifting frame. Afterward, the extensible frame is moved endwise so as to carry the stacker head away from the pivot of the lifting frame. The parts are so mounted and arranged that they are brought into play slowly and gradually, and actuate smoothly throughout, being a series of rocking movements.

The advantage in causing a distinct separation between the rear ends of the arms of

the extensible frame and the lifting frame 65 arms during the first stages of the lifting operation is that when the longitudinal movement of the extensible frame occurs, there are no extensive surfaces in sliding or frictional contact and consequently the draft 70 is reduced.

The full lines in Fig. 2 show the stacker with all slack taken out of the operating system and the bell crank levers actuated to a slight degree, although the stacker teeth 75 at their points are not clear of the ground. In other words, if the machine were at rest, the arms 52 of the bell crank levers would be parallel with the stacker head arms 23. When at rest, the bolts 62 can be transferred 80 from one set of holes through the arms 52 and the extensible frame arms, to another set of holes, without difficulty, as the holes align. When the stacker is at rest, the underside of the rearmost ends of the extensible frame arms are close to the lifting frame, the extent of separation amounting to the thickness of the pivot 47^a carried by the bearing block 47. At such time it is an easy matter to insert the pins 62 through the vertical holes 63-63^a in the rear ends of the arms of the extensible and lifting frames.

What I claim as my invention and desire to secure by Letters Patent, is:

1. A hay stacker comprising a base, a swinging lifting frame, an extensible frame carried thereby, and a lever connected with the lifting frame, the extensible frame, and the base, and operated by the swinging of said lifting frame to move said extensible frame relatively thereto.

2. A hay stacker comprising a base, a swinging lifting frame, an extensible frame carried thereby, and a bell crank lever mounted on said lifting frame and connected with the extensible frame and the base, said lever being operated by the swinging of said lifting frame to move said extensible frame relatively thereto.

3. A hay stacker comprising a base, a swinging lifting frame, an extensible stacker head carried thereby, a bell crank lever mounted on said lifting frame, one arm of said lever being connected with said stacker head, and a link connecting the other arm of said lever with the base.

4. A hay stacker comprising a base, a swinging lifting frame, an extensible stacker head carried thereby, a bell crank lever mounted on said lifting frame, one arm of said lever being connected with said stacker head, and a link connecting the other arm of said lever with the base in advance of the pivot of said lifting frame.

5. A hay stacker comprising a base, a swinging lifting frame, an extensible frame carried by said lifting frame, a stacker head carried by said extensible frame, a lever

- operatively connected with said extensible frame, means operated by the swinging of said lifting frame for actuating said lever to move said extensible frame relatively to the lifting frame, and means whereby said extensible frame may be fixedly secured to said lifting frame and said lever rendered inoperative.
6. A hay stacker comprising a base, a swinging lifting frame, an extensible frame carried by said lifting frame, a stacker head carried by said extensible frame, a lever fulcrumed on said lifting frame and connected with the base, and means detachably connecting said lever with said extensible frame.
7. A hay stacker comprising a base, a swinging lifting frame, an extensible frame carried by said lifting frame, a stacker head carried by said extensible frame, a lever fulcrumed on said lifting frame and connected with the base, and means adjustably connecting said lever with said extensible frame.
8. A hay stacker comprising a base, a swinging lifting frame, an extensible frame carried by said lifting frame, a stacker head carried by said extensible frame, a bell crank lever fulcrumed on said lifting frame and connected with the base, and means detachably connecting said lever with said extensible frame.
9. A hay stacker comprising a base, a swinging lifting frame, an extensible frame carried by said lifting frame, a stacker head carried by said extensible frame, a bell crank lever fulcrumed on said lifting frame and connected with the base, and means adjustably connecting said lever with said extensible frame.
10. A hay stacker comprising a base, a swinging lifting frame having side members, an extensible frame having side members carried by said lifting frame, bell crank levers mounted on the side members of the lifting frame and having one of their arms connected with the side members of the extensible frame, and links connecting the other arms of said levers with the base.
11. A hay stacker comprising a base, a swinging lifting frame having side members, an extensible frame having side members carried by said lifting frame, bell crank levers mounted on the side members of the lifting frame and having one of their arms connected with the side members of the extensible frame, links connecting the other arms of said levers with the base, and braces connecting the arms of said levers.
12. A hay stacker comprising a base, a swinging lifting frame, an extensible frame carried thereby, and a bell crank lever fulcrumed upon the lifting frame in advance of the pivots thereof, one arm of said lever being connected with the base below the horizontal plane of the lifting frame pivots and in advance thereof, the other arms of said lever being operatively connected with said extensible frame.
13. A hay stacker comprising a base, a swinging lifting frame, a stacker head carried by said lifting frame and movable angularly relatively thereto, and means operated by the swinging of said lifting frame for moving said stacker head angularly.
14. A hay stacker comprising a base, a swinging lifting frame, a stacker head carried by said lifting frame and movable angularly and longitudinally relatively thereto, and means operated by the swinging of said lifting frame for moving said stacker head angularly and longitudinally.
15. A hay stacker comprising a base, a swinging lifting frame, an extensible frame carried by said lifting frame and having a rocker bearing thereon, and means operated by the swinging of said lifting frame for rocking said extensible frame relatively to said lifting frame.
16. A hay stacker comprising a base, a swinging lifting frame, an extensible frame carried by said lifting frame and having a rocker bearing thereon, and a lever mounted on said lifting frame and operated by the swinging thereof to rock said extensible frame relatively to said lifting frame.
17. A hay stacker comprising a base, a swinging lifting frame having side members, an extensible frame carried by said lifting frame and comprising side members mounted to rock upon said lifting frame and to move longitudinally thereof, and a lever connected with the lifting frame, the extensible frame, and the base, for moving said extensible frame angularly and longitudinally.
18. A hay stacker comprising a base, a swinging lifting frame, rocking supports carried by the forward end portion of said lifting frame, an extensible frame mounted on said rocking supports and movable longitudinally thereon, and means actuated by the swinging of said lifting frame for rocking said extensible frame and moving the same longitudinally.
19. A hay stacker comprising a base, a swinging lifting frame, rocking supports carried by the forward end portion of said lifting frame, an extensible frame mounted on said rocking supports and movable longitudinally thereon, and a lever mounted on said lifting frame and means operated by the swinging of said lifting frame for rocking said extensible frame and moving the same longitudinally.
20. A hay stacker comprising a base, a swinging lifting frame, rocking supports carried by the forward end portion of said

lifting frame, an extensible frame mounted on said rocking supports and movable longitudinally thereon, and a bell crank lever mounted on said lifting frame and means 5 operated by the swinging of said lifting frame for rocking said extensible frame and moving the same longitudinally.

21. A hay stacker comprising a base, a swinging lifting frame, rocking supports 10 carried by the forward end portion of said lifting frame, an extensible frame mounted on said rocking supports and movable longitudinally thereon, a lever mounted on said

lifting frame and connected with said extensible frame, and a link connecting said 15 lever with the base.

22. A hay stacker comprising a base, a swinging lifting frame, rocking supports carried by the forward end portion of said lifting frame, an extensible frame mounted 20 on said rocking supports and movable longitudinally thereon, a bell crank lever mounted on said lifting frame and connected with said extensible frame, and a link connecting said lever with the base.
